UNITED STATES PATENT OFFICE

JOHN D. MACLACHLAN, OF KANSAS CITY, MISSOURI, ASSIGNEE, BY MESNE ASSIGNMENTS, TO MAC-AD-CO., OF KANSAS CITY, MISSOURI, A CORPORATION OF MISSOURI

AUTOMATIC ADVERTISING MACHINE

Application filed August 20, 1928. Serial No. 300,627.

This invention relates to automatic advertising devices of that general class in which different advertisements are successively displayed. As distinguished from the conventional types in which advertisements are successively flashed on a screen or displayed by the travel of a web which can be seen in motion my object broadly is to produce a display device in which is combined 5 an intermittently movable web or apron composed of advertising sections corresponding in width to the distance travelled in each intermittent movement, with means for hiding each section from view as it is moving 10 to or from the display point and for uncovering each section as or after it comes to rest at the display point. More specifically my object is to produce a display device in 15 which is provided a movable curtain which passes the display point and in such action 20 shuts from view an advertisement at such point and almost immediately thereafter in passing such point exposes to view another advertisement at the display point.

Another object is to provide a construction 25 composed of an intermittently moving web containing advertisements, and a continuously moving curtain which effects the intermittent movement of the web and exposes the advertisements successively at a 30 display point.

A further object is to provide a continuously moving curtain which effects a change 35 in position of advertisements at a display point, and in accomplishing such result hides from view the movement of the advertisements so that the latter are always at rest when being displayed and only one can be 40 displayed at a time.

Another object is to provide a construction 45 including an intermittently movable web made up of detachably linked advertising sections of equal size, for convenience in either shortening or lengthening the web by removing or adding a section or sections, and a further object is to provide a construction 50 in which the working mechanism is removably housed in a casing, so that it shall be possible to remove the working mecha-

nism as a unit from the casing for repair purposes or for replacement by another unit.

A still further object is to provide a device of the character outlined which can be manufactured economically, and possesses 55 the desirable qualities of simplicity, strength, and durability, and which will be equally serviceable upon a stationary or travelling support.

With the general objects in view mentioned, the invention consists in certain novel and useful features of construction and combinations of parts as hereinafter described and claimed; and in order that it may be fully understood, reference is to be had to 60 the accompanying drawing, in which:

Figure 1 is a front elevation of the device with part of the front wall omitted.

Figure 2 is a vertical section taken on the line II—II of Figure 1.

Figure 3 is a fragmentary plan view with the top wall of the casing omitted and certain parts broken away.

Figure 4 is a fragmentary vertical section showing the relative positions of certain 70 movable parts just prior to the intermittent actuation of one of them by the other.

Figure 5 is a fragmentary perspective view showing the said movable parts of Figure 4 in the position they occupy just before 80 one of them ceases to impart movement to the other.

Figure 6 is a fragmentary perspective view showing two of the advertising sections in disconnected relation.

Referring now to the drawings in detail, 85 1 indicates a casing provided with a window 2 in its front wall through which the advertisements are viewed, as successively displayed by an endless web or apron 3. The 90 web or apron extends vertically between and over a pair of guide rollers 4 respectively located within the casing and spaced slightly back of the front wall thereof at the bottom and top of the window, so that at 95 proper times, an advertisement appearing on said vertical portion of the web may be observed through said window. The web to have a large display capacity within a 100 relatively small casing, also extends around

a plurality of rollers 5 suitably journaled within the casing, and around another series of rollers 6 within the casing, but preferably journaled in a swinging frame 7 pivoted at 8 to a skeleton frame 9 removably arranged within the casing. To hold the web or apron, which engages all of said rollers, under proper tension regardless of weather conditions which may tend to cause it to shrink or expand slightly, any suitable means are employed. It is preferred however, in accomplishing such result, to mount all of the rollers 6 on the frame 7, as shown, so that only slight swinging movement of the latter shall be necessary to accommodate a relatively large shrinkage or expansion of the web. As the arrangement described provides for simultaneous take-up or extension of all of the horizontally-extending portions of the web, it is possible to shorten the web by removing an advertising section or to increase its length by inserting an additional section. If the sections are narrow the above statement applies to the removal or insertion of a plurality of sections. The means for holding the swing frame so that the web shall be taut at all times, consists of a spring 10, the spring being mounted on a rod 11 extending longitudinally of the casing and pivoted at 12 to a cross bar 13 of the frame 7, the spring 10 bearing at its rear end against a collar 13^a, and at its front end against a guide or support 14 secured to the frame 8 in any suitable manner and constituting a guide in which the rod 11 is slidably mounted. Shrinkage of the web or apron results in a slight forward movement of the swing frame against the resistance of the spring, and the latter, in the event stretching of the web occurs, reverses the movement of the swing frame and thus maintains the web in stretched or taut condition.

The web may be of any suitable construction equipped at regular distances apart substantially corresponding to the distances between the axes of rollers 4, with projections for successive engagement by an actuating means, as hereinafter explained. Each of the sections will carry an advertisement and at opposite sides thereof the projections mentioned are located. As exemplified, the sections at such opposite sides are provided with alined loops 15, the loops at each side being spaced apart to accommodate and receive between them the corresponding loops of adjacent preceding and following sections, and the projections mentioned are in the form of bars which extend through the alined loops of adjacent sections and thus connect them with a hinge relation, the rods preferably projecting beyond the side margins of the sections and rollers over which the web extends, as indicated at 16.

To effect intermittent or step-by-step operation of the advertising web and to move it each time a sufficient distance to withdraw one section from view and replace said section by the following section, the following construction is provided: 17 indicates a pair of endless sprocket chains which extend around sprocket wheels 18 mounted on shafts journaled in the frame, and around a pair of front sprocket wheels 19 and 20 also mounted on shafts suitably journaled in the frame. Any suitable means may be employed for effecting operation of the sprocket wheels, but the preferred construction is to provide the shaft of sprocket wheels 20, with a worm wheel 21 meshing with a worm 22 on the shaft of an electric or equivalent motor 23 on the frame as shown, or at any other convenient point. Spanning the spaces between and attached to the sprocket chains in any suitable manner, preferably so that it is readily detachable, is a curtain 24. The curtain is of such length that when its advanced end attains a position at the top of the window—if the curtain is moving upwardly—90 it completely hides the advertising section otherwise visible through the window, and also underlies and spans the following advertising section. At a point about midway the length of the curtain, the chains are 95 provided with dogs or lugs 25, so that when that portion of the curtain in advance of the dogs or lugs has spanned the window and thus hidden from view the advertising section behind the window, the dogs or lugs 100 engage the projections 16 at the lower side of said hidden advertising section and impart travel to the web. When this travel has transferred the engaged projections 16 from the plane of the lower rollers 4 to the plane 105 of the upper rollers 4, the formerly exposed advertising section is out of view and the following advertising section has attained the vertical position mentioned between rollers 4 and 4, but its attainment of such position was unobservable through the window 110 because the rear half of the curtain covered it. As the following section replaces the section previously disclosed, the dogs or lugs pass out of engagement with the engaged 115 projections 16, due to the fact that the latter change their direction from an upward to a rearward movement. As the dogs become disengaged, the movement of the advertising web ceases, but the movement of the curtain continues and thus exposes through the window the advertising section remaining stationary until the front half of the curtain has made nearly a complete circuit 120 within the casing, and has again assumed a position between the window and the vertical portion of the advertising web. As the latter is thus hidden from view, the dogs or lugs 25 engage the projections 16 occurring 125 between the section covered by the front 130

portion of the curtain and the following section, so that motion shall be imparted to the web to move the advertising section from behind the window and replace it by the following section, and immediately after this occurs the dogs or lugs pass out of engagement with the web projections, all subsequent operations being repetitions of those already described. It will thus be understood 5 that the advertising sections of the web are successively displayed through intermittent movement or travel of the web effected by continuous movement or travel of the curtain, and that the size and movement 10 of the latter is such that the observer cannot determine what effects the change of advertisements, as the web is always at rest when the advertisements are displayed.

If it is desired the interior of the casing 20 may be illuminated by electric lamps emitting light of any color or combinations of colors which may be desired or which 25 lend to the attractiveness of the display.

A device of the character described should 25 be desirable, especially for street car advertising, and window and store advertising, as it can be made and operated at a low cost, and without requiring constant or frequent supervision of skilled operators, and which 30 furthermore, is not objectionable on the ground of fire hazard. It is also of such construction that the advertising sections can be easily removed and new ones as 35 quickly substituted, it being of course understood that convenient accessibility to the web is desirable, for example, by making the top of the casing in the form of a door 40 27, it being noted that when a section is to be removed or replaced, the motor can be operated by hand until a particular section of the web is accessible through the top of the casing when the door thereon is opened. Another feature to which attention should be 45 called, is that the working mechanism as a 50 unit, is removable from the casing either through the door opening mentioned or by having another wall of the casing in the form of a door. By such construction, it will be possible to conveniently make 55 changes of units when necessary or desirable, and by having the unit removable, changes or repairs of the advertising web or any other part can be more conveniently made, as the unit can be taken to a factory or 60 repair shop, a new unit replacing it in the casing so that the use of the device need not be interrupted for a substantial period of time because of the necessity or desirability 65 of making changes or repairs. While the 65 continuously travelling curtain described is the preferred construction because of its simplicity, positiveness of action and infrequent necessity of repair, it is also desirable because it provides on its outer face for any suitable matter on which it is desired to

center the public's attention, that is to say, it may contain a notice referring to the advertisements on the web or to a sale to occur on a specified date or any other matter. The curtain is of course removable from the 70 sprocket chains for replacement by another containing a different notice or advertisement, or the curtain may be permanently affixed to the chains and provision made for detachably securing an advertisement upon 75 its outer side.

It will be further understood that while the continuously moving curtain is preferred to perform the functions hereinbefore set forth, it is possible to substitute a rotary 80 shutter or slide for hiding the web from view while in motion, and through suitable conventional mechanism, incidentally effect the operation of the web.

From the above description, it will be apparent that I have produced an automatic advertising device which embodies the features of advantage set forth as desirable in the statement of the objects of the invention, and which may be modified or varied without departing from the principles of construction and mode of operation involved or from the spirit and scope of the appended 90 claims.

I claim:

1. An advertising machine comprising a casing having a display window, an endless web containing matters for successive display at said window, driven means within the casing, and completely surrounding the 100 web means actuated by the driven means for periodically moving the web to withdraw display matter thereon from a display position at said window and dispose other display matter in display position at said 105 window, and means movable constantly with the driven means for interposition between the web and window during movement of the former.

2. An advertising machine comprising a 110 casing having a display window, an endless web containing matters for successive display at said window, continuously driven means within the casing, and completely surrounding the web means actuated by the 115 driven means for periodically moving the web to withdraw display matter thereon from a display position at said window and dispose other display matter in display position at said window, and means constantly 120 movable with the driven means for interposition between the web and window during movement of the former.

3. An advertising machine comprising a 125 casing having a display window, an endless web composed of transversely-extending advertising sections, rollers for guiding said web so that the advertising sections shall replace each other in rotation in occupying a 130 display position at said window, driven

means completely surrounding the web for periodically moving the latter to withdraw one advertising section from a position opposite the window and replace it by another, and means movable with the driven means, 5 for interposition between the web and window opening during the withdrawal action of one advertising section and its replacement by another.

10. 4. In an advertising machine, a casing provided with a window, an endless web composed of sections, within the casing, guide rollers for the web and for holding each section thereof successively opposite the window, an endless driven means within 15 the casing, completely surrounding the web means whereby said driven means shall periodically effect movement of the web to withdraw one section thereof from the window and replace it with another, and a curtain 20 carried by said driven means for interposition between the window and the adjacent portion of the web for substantially the full area of the window when the web is in motion.

25. 5. In an advertising machine, a casing provided with a window, an endless web within the casing, composed of transversely extending sections, guide rollers for the web and for holding each section thereof successively opposite the window, an endless driven means within the casing, completely surrounding the web means whereby said driven means shall periodically effect movement of the web to withdraw one section 30 thereof from the window and replace it with another, and a curtain carried by the driven means and of about twice the length of the window opening, and interposed between the 35 window and the displayed section of the web as said section is being withdrawn from its position adjacent the window and another section is replacing it.

40. 6. In an advertising machine, a casing having a window, guide rollers within the casing, an endless web composed of advertising sections of length about equal to the height of the window and provided at the junction of the sections with lateral projections, 45 driven chains within the casing provided with fixed dogs for successively engaging the projections of the web to impart movement thereto a distance about equal to the height of the window and then pass out of 50 engagement with such projections, and a curtain carried by said chains and of about twice the length of the window opening for covering a displayed section and retaining such relationship to said section until it has 55 been moved from view through the window.

60. In testimony whereof I affix my signature.
JOHN D. MACLACHLAN.
